UNITED STATES PATENT OFFICE.

HENRY WURTH, OF SCHENECTADY, NEW YORK.

BASKET-BALL GAME.

Application filed April 20, 1926. Serial No. 103,351.

My invention relates to games, and has for its object the provision of a game played on a game board and patterned after the game of basket ball.

In carrying out my invention in one form I provide a game board on which is shown in miniature a basket ball court together with various designating positions, and a spinner device arranged to operate over suitably marked dials whereby the movement of the ball from player to player and over the basket ball court is determined.

For a more complete understanding of my invention reference should be had to the accompanying drawings in which Fig. 1 is a plan view of the field of play; Fig. 2 is a plan view of the playing dials; Fig. 3 is a side elevation view of a spinner device, while Fig. 4 is an elevation view of a man used in playing the game.

Referring to the drawing, I have shown my invention in one form as applied to the game of basket ball, although it will be understood that the same principles of play are applicable to various other games. The game board may be arranged in any suitable manner in one or more parts. As shown the game board comprises two rectangular parts 10 (Fig. 1) and 11 (Fig. 2), which it is contemplated will be printed or otherwise inscribed on a single board or inscribed on separate boards hinged together so that the two parts may be folded together in the manner often used in checker boards for example. The part 10 of the game board has inscribed thereon a miniature basket ball court 12 provided with the usual foul lines and with a central starting circle 13. On the basket ball court are five plain circles which may be designated as "white". These white circles, representing one team, are placed in the positions occupied by the players at the beginning of an actual basket ball game and are indicated by the reference numbers 1 to 5 inclusive. There are also five stippled circles which may be termed "black" and these black circles, representing the oppos-

ing team, are likewise placed in the positions the players of this team would occupy at the beginning of the basket ball game and are represented by reference numerals 1-5 inclusive.

The board 10 also has four white out-of-bounds positions outside of the court 12 which are represented by white circles 14-17 inclusive, and four black out-of-bounds positions represented by black circles 18-21 inclusive. In the following description it will be understood that the term "white" refers to plain spaces white, "black" refers to stippled spaces.

At opposite ends of the court 12 are suitable score boards 22 and 23 for the two white and black teams respectively, each comprising a pointer 24 which may be moved over a dial to indicate numbers arranged in a circle.

The part 11 of the game board (Fig. 2) is provided with five charts or dials, a central starting dial 25, black playing dials 26 and 27, and white playing dials 28 and 29. A spinner device or indicator 30 (Fig. 3) is provided for use with the dials. This spinner device consists of a base member 31 on which a balanced pointer 32 is free to turn. A pin 33 is provided on the base 31 and this pin fits in an aperture or recess 34 provided in the center of each of the dials. A man 35 (Fig. 4) is also provided. This man is used to mark the position of the ball on the part 10 of the board.

It will be observed that the dials 25-29, inclusive, are each divided into sectors, some being plain, i. e., white, and some being stippled, i. e., black. These sectors are appropriately labeled to designate the action and various events of a basket ball game. The dial 25, for example, is divided into eighteen sectors, nine black and nine white. There are two each, both black and white, numbered 2, 3 and 4, and one black #5 and white #5, also one white foul, one black foul, one white out-of-bounds and one black out-of-bounds. It will be noted that the foul

and out-of-bounds sectors are each one half the size of the other sector which are of uniform size.

The dial 26 has 32 sectors labelled as fol-

lows:—

3	white	jump ball
1	"	out-of-bounds
1	"	technical foul
2	black	#1
1	"	#4
2	"	#5
13	"	goal
1	"	technical foul
1	"	out-of-bounds

15

Also the dial 26 has 16 peripheral sections 26^a which are used in stalling. These sections are of uniform size and they are labelled as follows:

20

1	black	#1
1	"	#2
1	"	#3
2	"	#4
2	"	#5
1	"	foul
1	"	out-of-bounds
1	white	#1
1	"	#2
1	"	#4
3	"	foul
1	"	out-of-bounds

30

The dial 29 has 32 sectors which are labelled approximately the reverse of dial 26 as follows:

35

2	black	#1
2	"	#2
3	"	#3
1	"	out-of-bounds
1	"	technical foul
2	white	#1
1	"	#4
2	"	#5
13	"	goal
1	"	technical foul
3	"	jump ball
1	"	out-of-bounds

40

Also the dial 29 has 16 peripheral sections 29^a which are used in stalling. These sections are of uniform size and they are labelled as follows:—

45

1	white	#1
1	"	#2
1	"	#3
2	"	#4
2	"	#5
1	"	foul
1	"	out-of-bounds
1	black	#1
1	"	#2
1	"	#4
3	"	foul
1	"	out-of-bounds

50

Also the dial 28 has out-of-bounds sections 37

The dial 27 has 32 sectors which are labelled as follows:—

1	white	#1	70
1	"	#2	
1	"	#3	
2	"	#4	
2	"	#5	
4	"	jump ball	75
1	"	2 on 1 foul	
1	"	out-of-bounds	
1	"	back talk foul	
1	"	holding foul	
2	black	#1	80
2	"	#2	
2	"	#3	
1	"	out-of-bounds	
1	"	pushing foul	
8	"	goal	85
1	"	double foul	

Also dial 27 has a plurality of sections 36 around its periphery which are used for out-of-bounds play. These sections are labelled as follows, the black sections being circumferentially twice the width of the white:—

1	black	#1	95
2	"	#2	
2	"	#3	
1	"	#4	
2	"	#5	
1	white	#1	100
1	"	#2	
2	"	#3	
2	"	#4	
2	"	#5	

105

The dial 28 also has 32 sectors, but these sectors are labelled approximately the reverse of the sectors of dial 27. Its sectors are labelled as follows:—

1	black	#1	115
2	"	#4	
2	"	#5	
1	"	2 on 1 foul	
1	"	out-of-bounds	
1	"	foul tripping	
1	"	holding foul	
3	white	#1	120
2	"	#2	
3	"	#3	
1	"	pushing foul	
8	"	goal	125
4	"	jump ball	
1	"	foul 2 on 1	
1	"	out-of-bounds	

130

Also dial 28 has out-of-bounds sections 37

around its periphery marked as follows, the white sections being circumferentially twice the width of the black:

5	1 black #1
	1 " #2
	2 " #3
	2 " #4
	2 " #5
10	1 white #1
	2 " #2
	2 " #3
	1 " #4
	2 " #5

15 In playing the game the man 35 is first placed on the central position 13 and the toss-up is determined by placing the indicator 30 on the center dial 25 and spinning. If the pointer stops on a black space, the 20 indicator is next placed on the black dial 27 and spun; if it stops on a white space the indicator is next spun on the white dial 28. In case the pointer, when spun on dial 25 stops on a white foul sector, the indicator 25 goes to dial 26, and if it stops on a black foul sector the indicator goes to dial 29. For example, if the indicator when spun 30 on the dial 25 stops on black #3, the man 35 is placed on black #3 on the field of play 10, and the indicator then placed on the black dial 27. As long as the indicator 35 stops on black spaces it is spun on dial 27 except in case of fouls when it is transferred either to dial 26 or dial 29, as previously noted. If the indicator when spun on dial 27 stops on a white space (other than a foul) it is transferred to dial 28. When the indicator stops on an out-of-bounds position 40 on any dial the outer sections 36 or 37, as the case may be, are read on the next spin, the section 36 being used for black out-of-bounds and the section 37 being used for white out-of-bounds.

45 Suppose now that the indicator when spun on the black dial 27 stops on white 4, the man 35 is then placed on white 4 of the field of play and the indicator placed on the white dial 28. Should the indicator when spun on the dial 28 stop on a black sector, as 50 5, the man will be placed on black 5 and the indicator placed on the black dial 27 and spun. The ball is transferred from man to man and from one team to the other in a similar manner when the out-of-bounds sections 55 36 and 37 are used.

When the pointer stops on a goal sector 60 on either of the dials 27 and 28, two points are counted for the side indicated by the color of the sector on which the pointer stops either white or black. The score may be conveniently recorded on the score boards 65 22 and 23. If the pointer stops on a goal sector on either of dials 26 and 29 one point is counted. In all cases when a goal is made

the indicator is next spun on the central 65 dial 25, the game then proceeding as previously described.

When the pointer stops on a jump ball section, the spinner is next transferred to the central dial 25 and spun, the game then 70 proceeding as previously described. Since the spinner goes to the central dial after stopping on a jump ball, it will be obvious that the jump ball spaces in reality are neither white nor black, although they have 75 been shown white.

For fouls, if the pointer stops on a white foul, spin on black foul dial 26 reading on the sectors, and if the pointer stops on a black foul spin on the white foul dial 29, 80 reading the sectors.

When either side desires to stall the remainder of the period of play, the indicator is placed on either dial 26 or 29, as the case 85 may be, and the pointer read with respect to the circumferential sections 26^a or 29^a of these dials.

The various markings on the dials are so arranged that the game closely approximates an actual basket ball game. It has 90 been observed, for example, that the sectors or sections are of different sizes and that certain markings occur more often than others, all of which is for the purpose of 95 approximating an actual game.

It will be observed that the starting dial 25 takes the place of the toss-up, the probability then being that one of the players 100 will get the ball, although a foul may occur and the ball may go out-of-bounds. The black playing dial 27 and also the black foul dial 26 are made up mostly of events with the ball retained in the possession of the black team although provision is made for the ball being obtained by the white 105 team. In like manner the white playing dial 28 and the white foul dial 29 are made up of events with the ball retained in the possession of the white team although provision is made for the ball being obtained by 110 the black team.

It may be helpful to a clear understanding of the invention to follow out in detail a typical game. Assume that the spinner is 115 spun on central dial 25 stopping on white 2. It is then spun on white dial 28 and assuming it stops on jump ball, it is returned to dial 25 and spun again. Since the spinner always goes to the central dial 25 after a jump ball, it will be obvious that the jump ball is neither black nor white, although it has been indicated by white spaces. Assuming the pointer now stops on black 5, the spinner is next spun on black dial 27. If it 120 stops now on a white foul, such as white 125 back talk foul, it is next spun on white foul dial 29. Supposing the spinner now stops on a white goal on dial 29, one point is

counted for the white team and the spinner next spun on the central dial 25. Assuming the pointer now stops on white out-of-bounds, it is next spun on white dial 28, 5 reading the outer segments 37, and if it stops on black 3, it is next spun on black dial 27. If it stops now on a black goal, two points are counted for the black team and the spinner next spun on the central 10 dial 25. Let it be assumed now that the spinner stops on a black foul on the dial 25, it is then next spun on the black foul dial 26. If it should now stop on white black goal, two points are counted for the black 15 team, and the spinner next spun on the central dial 25. During the progress of the game, the man 35 is moved from player to player, as indicated by the numbered black and white circles on the field of play 12. For 20 out-of-bounds positions the out-of-bounds positions 14-21 will be used, the man being placed on the nearest circle of the proper color. For example, if a foul is made with the ball in the possession of black player 25 No. 4, the man 35 would be placed in the black circle 18, and if a foul should occur with the ball in the possession of the white player 4, the man would be placed on the circle 16. As previously mentioned when 30 the time for play is nearly up and the winning party desires to stall for the remainder of the time, or if either party wishes to stall for any reason whatever, the spinner, when transferred in the regular course of the play 35 to his dial white 29 or black 26, as the case may be, may be read with respect to the outer segments 29^a or 26^a for stalling, the rules previously stated applying in this case also.

40 What I claim as new and desire to secure by Letters Patent of the United States, is:

1. A basket ball game comprising a game board provided with a field of play with designated positions thereon for the players of two opposing teams, a chart of the possible events of the game arranged in accordance with the probability of their occurrence, and means cooperating with said chart for indicating the occurrence of each event.
- 45 2. A basket ball game comprising a game board provided with a field of play with designated positions thereon for the players of two opposing teams, a playing dial for each team, and indicating means cooperating with said dials to determine the course of the ball.
- 50 3. A basket ball game comprising a game board provided with a field of play with designated positions thereon for the players of two opposing teams, a playing dial for each team, a foul dial for each team, and

spinner means used with said dials to determine the course of the ball.

4. A basket ball game comprising a game board provided with a field of play with 65 designated positions thereon for the players of two opposing teams, a playing chart for each team having indicated thereon the various possible events of the game in the order of their possible occurrence when the 70 corresponding team has the ball, a foul chart for each team having indicated thereon the various possible events of the game when a foul occurs, and means cooperating with said charts for indicating the occurrence of 75 the events.

5. A basket ball game comprising a game board provided with a field of play with designated positions thereon for the players of two opposing teams, and with a plurality 80 of charts including a starting chart, a playing chart for each team and a foul chart for each team, said charts being marked with the various possible events in the game and said playing charts being provided with 85 out-of-bounds positions and said foul charts with stalling positions, and means cooperating with said chart for indicating the occurrence of each event.

6. A basket ball game comprising a game 90 board, one part being provided with a field of play, and the other part being provided with a plurality of dials including a starting dial, a playing dial for each team, and a foul dial for each team, said dials being 95 marked with the various possible events in the game and said playing dials being provided with out-of-bounds positions and said foul dials with stalling positions, and spinner means cooperating with said dials 100 for determining the occurrence of the events.

7. A basket ball game comprising a game board provided with a field of play having designated positions thereon for the players of two opposing teams, a playing dial for 105 each team having indicated thereon the various possible incidents in the course and disposal of the ball with respect to the designated position of the players of the field of play, a foul dial for each team having indicated thereon the various possible incidents in the course and disposal of the ball when a foul occurs, and spinner means 110 adapted to be used with said dials to determine the progress of the game, said dials being so arranged that the progress of the game as determined by the spinner means closely approximates an actual basket ball game.

In witness whereof, I have hereunto set 120 my hand this 19th day of April, 1926.

HENRY WURTH.
